RINGING TOY BELL

Abraham Damast, Great Neck, N. Y., assignor to
 Criterion Bead & Novelty Corp., Long Island
 City, N. Y., a corporation of New York

Application December 23, 1948, Serial No. 66,899

3 Claims. (Cl. 177—7)

1

This invention relates to new and useful improvements in ringing toy bells.

In prior constructions of ringing toy bells it has been customary to connect an operator directly to the bell in order to swing the bell back and forth to make it ring. This construction is objectionable since the operator, which is connected with the bell at all times, dampens the crystal clear ringing of the bell.

This invention has for an object to so construct the ringing toy bells that the mechanism which swings the bells for ringing them is not permanently connected to the bells in order to avoid dampening at all times the crystal clear ringing quality of the bells.

More particularly, it is proposed to construct each bell with a vertical axis solenoid coil through which a vertical solenoid core is freely slidable. It is proposed to limit downward motion of the solenoid core to a position projecting from the bottom of the coil in order that the core may move into an up position when the coil is energized. An electric circuit with an interrupter is connected with the coil for periodically energizing it for periodically moving the core up. It is proposed to construct the bell with a dome shaped top and to swingingly connect the center of said dome shaped top with the bottom of the solenoid core so that the bell will move up and down with the core. It is contemplated that the bell be provided with the usual swingingly mounted clapper for striking and ringing the bell when the latter swings.

It is an important object of this invention to arrange a cam on the bottom of the solenoid coil engageable with the dome shaped top of the bell for swinging said bell laterally in one direction when said solenoid core moves to its top position in order that said bell will swing laterally in the other direction due to gravity when said bell moves down. It is proposed that said core move down a sufficient distance in reaching its down position in order that said swinging bell avoids hitting or touching said cam on the down motion of the solenoid core so as not to muffle the crystal clear ringing quality of the bell at this time.

It should be noted that the bell will only be touched by the cam on the up stroke of the solenoid core. The ringing of the bell will be slightly muffled during this period. However, it is proposed that the bells be used in a plurality of sets so that the muffled periods are staggered and during the greater period of the ringing operation the sound will be crystal clear. It is proposed that the muffled rings provide an interesting background for the clear rings of the bell.

Another object of the invention resides in arranging the cam as close as possible to the center of the dome-shaped top of the bell in order to have sufficient leverage to swing the bell through

2

a relatively large arc, and furthermore in order to reduce the dampening effect of the ringing bell. It is known that the closer the bell is touched to the center of the top, the less interference there will be with its ringing.

Another object of the invention is the construction of a device as described which is simple and durable and which may be manufactured and sold at a reasonable cost.

10 For further comprehension of the invention, and of the objects and advantages thereof, reference will be had to the following description and accompanying drawing, and to the appended claims in which the various novel features of the invention are more particularly set forth.

15 In the accompanying drawing forming a material part of this disclosure:

Fig. 1 is an elevational view of a group of ringing toy bells, illustrated in an inoperative position.

20 Fig. 2 is a fragmentary vertical sectional view of one of the bells, illustrated in a position in which the solenoid core is up.

25 Fig. 3 is a view similar to Fig. 2 but with the bell illustrated in a position in which the solenoid core is down and the bell has swung to the fullest extent in the other direction.

The ringing toy bells, in accordance with this invention, includes a set of bells each of which 30 is provided with a vertical axis solenoid coil 10 through which a vertical solenoid core 11 is freely slidably mounted. The core 11 is associated with means for limiting its downward motion to a position projecting from the bottom of the coil 10 in order that the core 11 may move to an up position when the coil 10 is energized. This means comprises a non-magnetic stud 12 which is mounted coaxially on the top of the core 11 and arranged so that its head engages the top of the coil 10 to limit downward motion of the core 11.

35 A bell 14 having a dome-shaped top 15 is swingingly connected at its center with the bottom of said core 11. This swinging connection is accomplished with a small hook 16 mounted on the bottom of the core 11 and engaging a small hook 17 mounted on the top of the bell 14. The bell 14 is also provided with a swingingly mounted clapper 18 for ringing the bell when the latter swings.

40 45 50 55 60 This clapper is swingingly connected with a bottom portion 19 of the hook 17. A cam 20 is mounted upon the bottom of the coil 10 and is engageable with the dome-shaped top 15 of the bell 14 for swinging the bell laterally in one direction when the core 11 moves to its top position in order that said bell 14 swings laterally in the other direction due to gravity. It is proposed that said core 11 move down a sufficient distance to its bottom position in order that said swinging bell 14 avoids hitting or touching the cam 20 so

as not to muffle the crystal clear ringing quality of the bell at this time.

The coil 10 is mounted in a non-magnetic tube 21, of cardboard or fiber. A fiber washer 22 is engaged into the bottom of the tube 21 against the bottom of the coil 10. The cam 20 is attached to said fiber washer 22. Preferably, the cam 20 is in the nature of a piece of wire having a cam-shaped bottom end 23. A fiber washer 24 is mounted in the top of the tube 21.

An electric circuit 25 is provided for a group of the bells 14 and is connected with the coils 10 of the bells for supplying the required electric current. The circuit 25 includes an electric current interrupter 26 for periodically interrupting the current to the coils 10.

The operation of the ringing bells may be understood from the following:

The interrupter 26 periodically interrupts the flow of current to the coils 10 of the group of bells. When current flows in the coils 10 the cores 11 move upwards to their top positions. This lifts the bells 14 upwards and causes the dome-shaped tops 15 to strike the cams 20, forcing the bells laterally in one direction. It is proposed that the cams 20 be quite close to the centers of the dome-shaped tops 15 in order to provide a mechanical leverage which will swing the bells 14 through a relatively large arc. Another reason for having the cams 20 close to the center of the dome-shaped tops of the bells is to reduce to a minimum the muffling effect of the cams 20 touching the bells while they are ringing.

When the current is interrupted to the coils 10 the solenoids become de-energized and the cores 11 and bells 14 fall to their down positions due to gravity. In the down position of the bells they are moved out of contact with the cams 20 and therefore swing from their original positions to positions in the other direction, as illustrated in Fig. 3. It is important that the parts be so designed that the bells 14 do not touch the cams 20 when swinging in said other directions so as not to muffle the ringing of the bells during these periods. Each bell will swing back and forth a number of times before it comes to rest, and during these swings will ring clearly since they are entirely free and are not being touched by any obstruction.

It is proposed that the bells be used in sets so that clear ringing bells will be staggered with some of the muffled rings occasioned when the cams 20 touch the dome-shaped tops 15 of the bells, in order that the muffled rings form a background for the clear rings of the bells.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In ringing toy bells, a vertical axis solenoid coil, a vertical solenoid core freely slidable through said coil, means for limiting downward motion of said solenoid core to a position projecting from the bottom of said coil in order that said core may move to an up position when said core is energized; a bell having a dome-shaped top swingingly connected at the center of its top with the bottom of said core and also having a swingingly mounted clapper for striking and ringing said bell when the latter swings, a cam mounted on the bottom of said coil and engageable with said dome-shaped top for swinging said bell laterally in one direction when said core moves to its top position in order that said bell swings laterally in the other direction when said bell moves down due to gravity, and said core moving down a sufficient distance to its down position in order that said swinging bell avoids hitting or touching said cam so as not to muffle the crystal clear ringing of said bell at this time.

ringing said bell when the latter swings, a cam mounted on the bottom of said coil and engageable with said dome-shaped top for swinging said bell laterally in one direction when said core moves to its top position in order that said bell swings laterally in the other direction when said bell moves down due to gravity, and said core moving down a sufficient distance to its down position in order that said swinging bell avoids hitting or touching said cam so as not to muffle the crystal clear ringing of said bell at this time.

2. In ringing toy bells, a vertical axis solenoid coil, a vertical solenoid core freely slidable through said coil, means for limiting downward motion of said solenoid core to a position projecting from the bottom of said coil in order that said core may move to an up position when said core is energized, a bell having a dome-shaped top swingingly connected at the center of its top with the bottom of said core and also having a swingingly mounted clapper for striking and ringing said bell when the latter swings, a cam mounted on the bottom of said coil and engageable with said dome-shaped top for swinging said bell laterally in one direction when said core moves to its top position in order that said bell swings laterally in the other direction when said bell moves down due to gravity, and said core moving down a sufficient distance to its down position in order that said swinging bell avoids hitting or touching said cam so as not to muffle the crystal clear ringing of said bell at this time, said cam being close to the center of said dome-shaped top in order to have sufficient leverage to swing said bell through a large arc.

3. In ringing toy bells, a vertical axis solenoid coil, a vertical solenoid core freely slidable through said coil, means for limiting downward motion of said solenoid core to a position projecting from the bottom of said coil in order that said core may move to an up position when said core is energized, a bell having a dome-shaped top swingingly connected at the center of its top with the bottom of said core and also having a swingingly mounted clapper for striking and ringing said bell when the latter swings, a cam mounted on the bottom of said coil and engageable with said dome-shaped top for swinging said bell laterally in one direction when said core moves to its top position in order that said bell swings laterally in the other direction when said bell moves down due to gravity, and said core moving down a sufficient distance to its down position in order that said swinging bell avoids hitting or touching said cam so as not to muffle the crystal clear ringing of said bell at this time, said means for limiting downward motion of said core comprising a non-magnetic headed stud mounted on said core and having its head engageable with the top of said coil.
